UNITED STATES PATENT OFFICE.

ELISHA HAWES, OF SACRAMENTO CITY, CALIFORNIA.

MACHINE FOR MAKING SHEET-METAL LATHING.

SPECIFICATION forming part of Letters Patent No. 388,866, dated September 4, 1888.

Application filed July 16, 1887. Serial No. 244,519. (No model.)

To all whom it may concern:

Be it known that I, ELISHA HAWES, a citizen of the United States, residing at Sacramento City, in the county of Sacramento and State of California, have invented a new and useful sheet-metal-working machine for making fencing and lathing and clinching and counter-clinching sheet metal together and punching holes in the same, as may be required for lathing, of which the following is a specification.

My invention relates to an improvement in machines for punching and shearing sheet metal; and it consists in the combination of devices hereinafter described.

In the accompanying drawings, Figure 1 is a top plan view of a punching and shearing machine embodying my improvements. Fig. 2 is a side elevation of the same. Fig. 3 is an end elevation of the same. Fig. 4 is a detail elevation of one side or standard of the frame. Figs. 5 and 6 are detail sectional views of one pair of the rolls, showing the punches and shears attached to one of said rolls. Fig. 7 gives detail views of the punches, and Fig. 8 gives similar views of the shears.

A represents the sides of the frame, which are of the form here shown, are provided at their lower corners with supporting-feet B, and in said sides are secured bearings C, D, and E. The feet B are bolted to a base-plate, F, and a pair of longitudinal bars, G, connect the upper edges of the sides.

H I represent two pairs of rolls, which are arranged one above the other and have their shafts journaled in the bearings C D, respectively. The rolls H are each provided with a spur-wheel, K, and the rolls I have spur-wheels L, of the same size as wheels K and meshing therewith, thereby gearing the upper rolls, H, to the lower rolls, I, in pairs. Each upper roll, H, has a series of threaded openings, M, arranged in a straight longitudinal line, and is further provided with annular grooves N, which may be either straight and at right angles to the axes of the rolls or angular and arranged obliquely to the axes of the rolls, as shown in Fig. 2. In the said grooves N are secured annular cutters or shears O, and in the openings M are screwed the inner ends of punches P. The said cut-

ters and punches project beyond the faces of rolls H, and are adapted to enter countersunk recesses R S, respectively, in the faces of rolls I. The said rolls are hollow, and are preferably made in longitudinal sections or sectors detachably secured together.

T represents a driving-shaft, which is journaled in the bearings E, and has at one end a driving-pulley, U, and at the opposite end an idle spur-wheel, V, which meshes with and connects the wheels L and is adapted to rotate the rolls at a uniform rate of speed when the shaft T is rotated, the proximate faces of the opposing rolls traveling in the same direction by reason of the wheels K L, which gear them together.

W represents a guiding-apron, which is arranged in a longitudinal plane on a level with the proximate faces of the pair of rolls, and Y represents a cover to said apron. The apron and cover are preferably made of boiler-iron to secure sufficient strength and rigidity, and are supported and maintained in position by suitable standards, X, as shown.

The operation of my invention is as follows: The sheet metal to be punched and sheared is fed between the first pair of rolls, and as the same rotate their punches P punch holes in the sheet metal when they register with the openings R, and the punches being somewhat smaller in diameter than the said openings, a boss is formed around each punched hole. The cutters O and countersunk grooves or recesses S cause the sheet metal to be cut or sheared into strips of suitable width, according to the points on the rolls at which the cutters are located. As the sheets of metal travel between the first pair of rolls and are forced rearward thereby, they come in contact with the guide-apron W and cover Y, which direct said sheets between the second pair of rolls, as will be readily understood. The function of the said second pair of rolls is to unite the edges of the sheared and punched sheets by clinching the same as the said sheets pass between them.

Having thus described my invention, I claim—

1. The combination of the revoluble rolls H I, having the projecting punches or cutters (or both) and the countersunk openings and

grooves or recesses on their opposing faces, for the purpose set forth, substantially as described.

2. The combination of the revoluble rolls 5 H I, having the projecting punches or cutters (or both) and the countersunk openings and grooves or recesses on their opposing faces, and the gears K L, connecting said rolls, substantially as described.

10 3. The combination of revoluble pairs of rolls H I, having the punches or cutters (or both) and the countersunk openings and recesses or grooves on their opposing faces, the gears K L, connecting said rolls together in 15 pairs, and the driving shaft T, having the gear-

wheel V, meshing with and connecting the gears L, for the purpose set forth, substantially as described.

4. The combination of the pairs of rolls geared together and having the projecting 20 punches or cutters (or both) and the countersunk openings or recesses on their opposing proximate faces, and the guiding-apron W, arranged between the said pairs of rolls, substantially as described.

ELISHA HAWES.
